US00D442853S

(12) **United States Design Patent** (10) Patent No.: **US D442,853 S**
Gopalraja et al. (45) Date of Patent: **** May 29, 2001**

(54) **ROUNDED OVERLAP COIL**

(75) Inventors: **Praburam Gopalraja**, San Jose; **John C. Forster**, San Francisco; **Michael Rosenstein**, Sunnyvale, all of CA (US)

(73) Assignee: **Applied Materials, Inc.**, Santa Clara, CA (US)

(*) Notice: This patent is subject to a terminal disclaimer.

(**) Term: **14 Years**

(21) Appl. No.: **29/109,893**

(22) Filed: **Aug. 24, 1999**

(51) LOC (7) Cl. **08-08**
